UNITED STATES PATENT OFFICE.

AUGUST W. HUTAF, OF HOBOKEN, NEW JERSEY.

DESIGN FOR A HAMMER.

SPECIFICATION forming part of Design No. 28,942, dated June 28, 1898.

Application filed May 6, 1898. Serial No. 679,963. Term of patent 3½ years.

To all whom it may concern:

Be it known that I, AUGUST W. HUTAF, a citizen of the United States, residing at Hoboken, in the county of Hudson and State of New Jersey, have invented a new and original Design for Hammers, of which the following is a specification, reference being made to the accompanying drawings, forming part thereof.

In the drawings forming part of this specification, Figure 1 is a side view showing my new design, and Fig. 2 an end view of the handle.

The leading and material feature of my design consists of a handle A, which is connected with a hammer B, and the hammer B is formed to represent the figure of a man, the head C of which is provided with a hat D, which constitutes the hammer proper, and the legs E of the figure are projected in line with the head. The arms E of said figure are folded adjacent to the side and the hands E² adjacent to the thighs. The handle A is also formed

to represent a man having a head a, a hat a², and arms a³, which are raised, and the hands a⁴ of which grasp the hands and thighs of the figure which represents the hammer, and the figure A, which represents the handle, is also provided with legs a⁵, having feet a⁶, one of which is provided at the toe with a backwardly-directed triangular notch or recess a⁷. 25 30

My design is applicable to all forms of hammers or similar devices.

Having fully described the same, I claim and desire to secure by Letters Patent—

The design for a hammer herein shown and described. 35

In testimony that I claim the foregoing as my invention I have signed my name, in presence of the subscribing witnesses, this 3d day of May, 1898.

AUGUST W. HUTAF.
